CLAIM

The ornamental design for a make-up compact, as shown and described.

DESCRIPTION

The design is for a make-up compact. In one embodiment, the design is a group of compacts connected together by a sole. In another embodiment, the design is an individual compact. In another embodiment, the design is a sole for connecting the individual compacts.

FIG. 1 is a perspective view of a make-up compact showing the design of this invention.

FIG. 2 is a front view thereof.

FIG. 3 is a back view thereof.

FIG. 4 is a left side view thereof.

FIG. 5 is a right side view thereof.

FIG. 6 is a top view thereof.

FIG. 7 is a bottom view thereof; and,

FIG. 8 is a perspective view thereof, and further showing a lid in an open position, FIGS. 1-7 showing the lid in a closed position.
